UNITED STATES PATENT OFFICE.

WILLIAM FRANCIS STACK, OF KNOXVILLE, TENNESSEE.

ILLUMINATED SIGN.

1,126,901.

Specification of Letters Patent.

Patented Feb. 2, 1915.

Application filed October 29, 1913. Serial No. 798,088.

To all whom it may concern:

Be it known that I, WILLIAM F. STACK, a citizen of the United States, residing at Knoxville, in the county of Knox and State of Tennessee, have invented a new and useful Illuminated Sign, of which the following is a specification.

This invention has reference to improvements in illuminated signs, and its object is 10 to provide a sign readily visible both in day light and at night, and which may be illuminated with a minimum number of light units.

In accordance with the present invention 15 the sign may be made wholly of opaque material with a light giving element or unit to the rear thereof, that is, back of the visible face, while the opaque material is so arranged as to present numerous illuminated 20 elements outlining the characters of the sign and which elements are so arranged as to be apparently evenly illuminated, although but a single source of light be employed, and the sign characters be located at different 25 distances from the source of light.

The sign is usually made of sheet metal with punched-out portions joined to the body of the sign by small or attenuated connecting parts, and these punched-out portions are bent rearwardly or away from the observed face of the sign at an angle thereto. The sign is made visible at night by the illumination of these punched-out portions from a source of artificial light housed within the 35 sign. This artificial illumination may be brought about very satisfactorily by means of a single source of light of much less extent in any direction than the sign or even a sign character, and in order to accomplish 40 this desirable result the punched-out portions are so arranged with respect to the source of light that their observed reflecting faces are all presented toward the source of light in substantially the same relation 45 thereto whereby each reflecting element directs through the face of the sign character substantially the same proportion of the light reaching it from the source of light as does each of the other reflecting elements. 50 This is true even though some of the sign characters be quite distant from the source of light and others be quite close to it.

The invention will be best understood 55 from a consideration of the following detailed description, taken in connection with

the accompanying drawings forming a part of this specification, with the further understanding that while the drawings show a practical form of the invention the latter is not confined to any strict conformity with the showing of the drawings, but may be changed and modified so long as such changes and modifications mark no material departure from the salient features of the invention.

In the drawings: Figure 1 is a face view of a sign constructed in accordance with the present invention and partly broken away to show a source of illumination within the sign. Fig. 2 is a section on the line 2-2 of 70 Fig. 1. Fig. 3 is a detail face view of one of the sign characters on a larger scale than Fig. 1. Fig. 4 is a detail section through one of the punched-out reflecting members. Fig. 5 is a perspective view of one of the 75 punched-out reflecting members on a larger scale than Fig. 4. Fig. 6 is a fragmentary view showing a slight modification in the form of the reflecting members or units.

Referring to the drawings there is shown 80 a sign made up of a face plate 1, another face plate 2 when the sign is of the double face type, and which may simply constitute the back wall of the sign when of the single face type, and there are provided connecting members 3 which may constitute the top, bottom and ends of the sign. The particular structure of the face plates and edge members does not enter into the present invention and hence no attempt has been 90 made to show the body of the sign otherwise than more or less diagrammatically.

Produced upon the face of the sign, and this means one or both faces in accordance with whether the sign is a single face or a 95 double face sign, there are sign characters 4, the simplest way of producing these sign characters being by painting them upon the face of the sign in some contrasting color to the body portion of the face 1 or 2 upon 100 which they are produced. This, however, does not preclude the formation of the sign characters in some other manner, the purpose being to provide for an attractive day light appearance.

Punched out from the face 1 or 2, as the case may be, or both, are reflecting elements or units 5 shown in most of the figures of the drawing as substantially circular, while in Fig. 6 the outline of these units simulates 110

the appearance of a small electric light bulb, as indicated at 5^a in Fig. 6. Whatever be the formation of the punched-out portion it is not usually completely severed 5 from the face plate, but is customarily connected thereto by a relatively attenuated integral portion 6, at which point the unit is bent away from the plane of the face of the sign toward the interior of the body portion of the sign. Furthermore, the reflecting units 5 are each shown as having a visible face 7 concave, although the concavity is not obligatory, but is to be preferred as enhancing the effect.

15 Mounted within the body of the sign is a light source 8 shown as an incandescent electric lamp, the showing being considered as typical of any suitable source of light and in practice a Mazda or tungsten incandescent electric lamp, or any other high efficiency lamp may be employed. Under some circumstances good effects may be produced by gas or oil lights, but for obvious reasons the electric light where available 20 is used. In order that the lamp 8 may be readily accessible it may be mounted upon a door 9 carried by the bottom member 3 or any other arrangement may be employed which permits access to the lamp for cleansing 25 or renewal. In the sign shown in Fig. 1 where the sign characters are in the form of letters of the alphabet spelling a word, the lamp 8 is placed about midway of the length of the sign and at a lower level than 30 the letters making up the sign. Now, in order that each reflecting unit 5 may be strongly illuminated the connection 6 is so related to the reflecting unit and the source of light that all the reflecting units have 35 the same or substantially the same angular relation to the source of light irrespective of their distance therefrom although their relation to each other varies with their distance from the source of light. The connection is therefore diametrically opposite 40 from that edge of the reflecting unit which is directed toward and nearest to the lamp 8 and the reflecting unit is bent upon the support 6 so as to project into the interior 45 of the sign at an angle to rays of light emitted by the lamp. The reflecting units are produced within the outlines of the sign characters and are associated to produce the sign characters so that they appear 50 to be made up of a properly arranged series of small units, thereby producing an attractive appearance at night, and, furthermore, the units are visible by day light and add to the attractiveness of the sign characters 55 in which they are located, the appearance both by day and night being somewhat similar to the familiar bull's eye type of illuminated sign characters. Moreover, the effect at night is quite close in appearance to the 60 bull's eye type of sign character, but with

the advantage of low cost of manufacture, freedom from injury and capability of quite even illumination with a single light source, a single twenty-five or forty watt tungsten lamp giving sufficient light to illuminate a 70 sign of commercial size including numerous sign characters with even those sign characters most distant from the light well illuminated and not noticeably less brilliant than those closer to the light source. 75

The feature of the present invention contributing to evenness of illumination and distinguishing the sign or sign character of the present invention from others of like type, is the arrangement of the reflecting units 5 or 5^a so that the line of connection of each unit with the face of the sign is substantially perpendicular to and bisected by a plane in itself substantially perpendicular to the face of the sign, if flat, and said plane includes 80 the source of light, the mid point of the reflecting unit and a point of the inner edge of the reflecting unit located in a diameter including the mid point of the connection of the reflecting unit with the face of the sign. 85 All such planes radiate from the source of light, and for this reason the reflecting units may be all described as in radial or substantially radial relation to the light source, such relation being the same for all the units 90 although the distances of the different light reflecting units from the source of light are unequal. This arrangement has been found in practice to cause the observed or reflecting faces of the reflecting units to have so 95 nearly the same brilliancy that the sign as a whole appears to be quite evenly illuminated despite the fact that some of the sign characters are quite close to the source of light and others quite distant therefrom. 100 The reason for this is that because of the relation of each reflecting unit to the common light source, each reflecting unit or element directs through the face of the sign or sign character substantially the same proportion of light reaching it from the source of light as does each of the other reflecting elements or units. The effect is further enhanced by making the visible face of each reflecting unit or element concave and the 105 intensity of illumination is apparently improved thereby as though by a condensation of the illumination. By a suitable proportioning of the degree of concavity of the visible faces of the reflecting units and the 110 degree of bending of these reflecting units into the interior of the sign an approximate evenness of illumination from a single light source may be brought about, but in all instances the line of bend is perpendicular, or 115 substantially so, to the light rays reaching the corresponding element. Hence each light reflecting element is in the same relation to the light source as all the others with the single exception of distance, but the effect of 120 125 130

distance may be modified to an appreciable extent by the angle of the reflecting elements to the plane of the visible face of the sign.

For small signs a single electric lamp of 5 small wattage, especially if of the high efficiency type, is sufficient, while for large signs the light giving means must, of course, be more intense. It can, however, be limited to a single approximately centrally located 10 light giving element or a circumscribed group of such elements acting in effect as a single light source. While for large signs it may be found advisable to employ more than one light giving element, the specified 15 arrangement of the light reflecting units to each distinct light giving element or group thereof is maintained, so that a single source of light, or a group acting effectively as a single source, and hence included under such 20 term as a single light giving element, will illuminate effectively several sign characters at one time, wherefore by the present invention the cost of illumination is reduced to a very low minimum without sacrificing 25 the appearance of the illuminated sign.

While the light reflecting elements have been described as punched out of the sign face and integrally connected therewith, it is to be understood that they may be otherwise formed and otherwise supported but so 30 as to all maintain the specified relation to the light source by which the results described are obtained.

The word "facing" as used herein with 35 respect to the relation of the reflecting elements to the source of light means that the reflecting face of each reflecting element of the sign, whether near to or distant from the one source of light, is turned toward such 40 source of light in the same manner, to the same extent, and to the same degree as all the other reflecting elements. Considering then the face of the sign as flat, the different reflecting elements each have the reflecting 45 face at a different angle to the face of the sign from that of any other reflecting element, the angles differing in accordance with the distances from the source of light. Since the facing position of the reflecting 50 elements to the single source of light is alike for all elements, rays of light emitted by the light source and striking the same relative point on each reflecting element have the same angle of incidence and angle of reflection for all the elements, this of course 55 being subject to such slight variations as might occur in any such structure. Therefore, though there be but one source of light at, say, a central point with the sign characters extending along the sign in opposite 60 directions from the source of light, all the reflecting elements will direct through the face of the sign to the eye of the observer substantially the same proportion of the 65 light reaching them.

What is claimed is:—

1. A sign having a group of sign characters each provided with a plurality of associated reflecting elements arranged in the lines of the strokes of the character, and 70 each element extending rearwardly from the observed face of the sign at an angle thereto, and the sign also being provided with a source of light common to all the sign characters and located back of the observed face of the sign, those portions of the reflecting elements that are visible through the front of the sign all facing the common source of light substantially alike, 75 and each being at an angle to the rays of light reaching it from the common source to reflect through the front of the sign to the eye of an observer substantially the same proportion of such light as each of the other elements. 85

2. A sign composed of a plurality of sign characters with a single source of illumination back of the observed face of the sign and located substantially intermediate of the length of the plurality of sign characters, each sign character having a series of light reflecting units or elements projecting at an angle to the plane of the sign character in a direction away from the observed face thereof and each reflecting element having the diameter extending from the mid point of the connection with the body of the sign to the opposite free edge located in a plane substantially perpendicular to the face of the sign character and 100 passing through the source of light. 95

3. A sign composed of a plurality of sign characters with a single source of illumination back of the observed face of the sign and located substantially intermediate of the length of the plurality of sign characters, each sign character having a plurality of light reflecting units or elements projecting at an angle to the plane of the sign character in a direction away from the observed face thereof and each reflecting element having the diameter extending from the mid point of the connection with the body of the sign to the opposite free edge located in a plane substantially perpendicular to the face of the sign character and 110 passing through the source of light, and each reflecting element also being concaved or dished on the observed face. 115

4. A sign composed of a plurality of sign characters with a source of light back of the observed face of the sign and located substantially intermediate of the length of the sign, each character including a plurality of light reflecting units fast at one side to 120 the face of the sign and projecting away from the observed face of the sign at an angle to the plane thereof, each reflecting unit irrespective of its distance from the source of light having the point of nearest 125 130

approach to the source of light most distant from the point of connection with the sign and located in a diameter which is in a plane substantially perpendicular to the face of the sign and passing through the source of light.

5. A sign having a face member of opaque material with a group of sign characters produced thereon in the form of integral portions of the face member extending in a direction away from the observed face of the sign at an angle thereto, and the sign being provided with a source of light back

of the observed face and substantially central to the length of the group of sign characters, all of said rearwardly extending portions being dished or concaved on the reflecting portions and all similarly facing the central source of light.

In testimony, that I claim the foregoing 20 as my own, I have hereto affixed my signature in the presence of two witnesses.

WILLIAM FRANCIS STACK.
